MERCHANDISE DISPLAY RACK

Robert L. Falkenberg, Kansas City, Mo., and Curtis J. Patterson, Jr., Mission, Kans.; said Patterson assignor to said Falkenberg

Application July 5, 1949, Serial No. 3,698

Term of patent 3½ years

(Cl. D80—9)

To all whom it may concern:

Be it known that we, Robert L. Falkenberg and Curtis J. Patterson, Jr., both citizens of the United States, residing at 7209 Central Avenue, Kansas City, in the county of Jackson and State of Missouri, and 6145 Lockton Lane, Mission, in the county of Johnson and State of Kansas, respectively, have invented a new, original, and ornamental Design for a Merchandise Display Rack, of which the following is a specification, reference being had to the accompanying drawing forming a part thereof.

Fig. 1 is a perspective view of a merchandise display rack, showing our new design.

We claim:
The ornamental design for a merchandise display rack, as shown.

ROBERT L. FALKENBERG.
CURTIS J. PATTERSON, JR.
